pany

Application August 12, 1946, Serial No. 689,988
In Great Britain March 15, 1945

13 Claims. (Cl. 101—114)

1

The present invention relates to a method and means for depositing films of metal on a series of plates or sheets and has been especially, although not necessarily exclusively, evolved for the purpose of depositing such a film on plates of mica intended to form the dielectric in electrical condensers. Heretofore it has been the practice to deposit such a film of metal either by a painting or spraying process, the material painted or sprayed, referred to in the following description and claims as "paint," being either a compound of the metal, which, by subsequent treatment, is reduced to the pure metal or the metal itself directly deposited in fine particles. The process is commonly referred to as "silvering," but, in the following description and claims, that term is to be understood as covering the application of metals other than silver; also the term "mica" is to be regarded as including other materials in sheet form to which the invention is applicable.

The invention is concerned with forming a metal deposit on successive plates by a spraying operation, which possesses certain advantages over forming the deposit by painting. Very generally it is not desired to cover the whole of either side of the mica or other plate to be silvered, but only a portion thereof, and for this purpose it has hitherto been the practice to spray the metal or metal compound on to the plate through a metal mask wherein there is cut an aperture determining the area on which the spraying operation is to take place. Obviously, a certain amount of the metal paint becomes sprayed on the marginal portion of the metal mask and it is necessary periodically to arrest the operation in order to clean this paint off; even if a duplicate mask be substituted while the mask which has been in use is cleaned, interruption in the continuous operation of spray painting is involved, and it is the main object of the present invention to overcome these and other disadvantages arising from the use of a metal mask.

According to the invention, in a spray painting operation as above set forth, a series of masks is cut in paper or other material of small value as compared with metal, each mask being discarded at or before the stage at which paint has been deposited on the margin of the aperture cut therein to such an extent as would require a cleaning operation. It may be found desirable to use the paper masks once only, but, on the other hand, they may be employed two or more times as found convenient. In any case, however, the paper or other material, referred to in

2

the following description and claims comprehensively as "paper," being relatively of small value, may be discarded when it has become useless owing to the encrustation of paint thereon. The apertures to form the masks might be cut in separate sheets of paper, but it is preferred to cut a series of apertures in a strip which may be wound off from a roll of paper and wound on to a second roll which is thus ready to provide a perforated strip constituting a series of masks. Preferably, however, the operation of cutting the apertures in a strip and the use of such a strip in a spraying operation are combined in a single machine.

15 In order that the invention may be clearly understood and readily carried into effect, it will now be described more fully with reference to the accompanying drawings which illustrate, by way of example, a machine suitable for silvering small mica sheets and wherein:

Figures 1 and 2 together constitute a plan view of the machine,

Figures 3 and 4 similarly show a side elevation and

25 Figures 5, 6, 7, 8 and 9 are respectively sections on the lines A—A, B—B, C—C, D—D, and E—E, Figures 5, 6 and 8 being to an enlarged scale.

The machine is of the type wherein the apertures constituting the masks are cut as a series in a strip of paper. The various items constituting the apparatus are mounted on a bedplate or bench 1, supported from which, by means of uprights 2, is a roll of paper strip 3, the mounting being such that the strip may readily be drawn 35 from the roll, but any suitable braking mechanism, not shown, since its construction does not form a feature of the present invention, is provided so that overrun of the paper is avoided. The strip 3 is lead over rollers 4, around a drum 5 and around a further roller 6: it then travels

40 horizontally, being suitably supported and guided, and is finally taken underneath a roller 7 to a winding-off roll 8. The various operations of the machine are derived from a shaft 9 continuously rotated from a suitable source of power, not shown, by means of a belt 10, pulley 11 and worm gearing housed in a casing 12. By means of bevel gearing 13, the shaft 9 drives a spindle 14 on which the winding-off roll 8 is mounted,

45 50 being driven therefrom through friction mechanism 15 so that continuous tension is maintained on the strip 3 between the rollers 6 and 8. For the purpose of the various operations of the machine it is necessary that the strip 3 shall 55 be moved forward in a step-by-step manner, this

being accomplished by means of a ratchet wheel 16 mounted on the spindle of the drum 5 and actuated by a pawl 17. This ratchet-and-pawl mechanism is operated from the shaft 9 by means of bevel gearing 18, serving continuously to drive a spindle 19, fitted with a disc 20 having a crank pin 21 which engages a connecting rod 22, the further end of which is pivoted to a lever 23 adapted to rock around the spindle of the drum 5 and carrying the pawl 17. Thus a rocking motion is imparted to the lever 23 and by the action of the pawl 17 the necessary step-by-step movement is transmitted to the drum 5 and thence to the strip 3. On account of the frictional drive of the winding-off roll 8 the strip is maintained taut in its passage through the machine.

For the purpose of forming in the strip 3 a series of apertures to constitute masks through which the spraying operation is performed, it is passed through a punching device constituted by a punching tool 24, Figure 5, carried by a member 25 adapted to be reciprocated relatively to a die 26. A plate 27 is also supported by springs 28 from the member 25, the punch 24 extending through the plate 27 when it operates to cut an aperture in the strip 3. On withdrawal of the punch, the plate 27 remains in contact with the upper surface of the die 26 so that the strip 3 is retained against the upward motion of the punch 24 in order to avoid tearing the strip: finally the plate 27 rises, liberating the strip 3 for its next step forward. The member 25 and elements attached to it are reciprocated periodically by means of a lever 29 with which the member 25 is connected by a pivoted link 30. The lever 29 is pivoted at a fixed point 31, its rear end being provided with a roller 32 bearing on a cam 33 carried by the shaft 9. A weight 34 on the rear end of the lever serves to raise the member 25 after passage of the cam 33 past the roller 32.

For the purpose of silvering the mica plates it is necessary to bring each one separately, while the strip 3 is stationary, to a point immediately above a spray gun 35, the location of this spray gun relatively to the punch being such that at each halt of the strip an aperture is immediately above the gun. In the machine illustrated, the latter is shown as fixed, but if the apertures in the strip 3 be above a certain size, in order that the corresponding area of each mica plate may be satisfactorily covered, it may be necessary that the gun shall be moved during the spraying operation. For this purpose it may be pivotally mounted and oscillated either continuously or during each halt of the strip by cam or other suitable mechanism actuated from the shaft 9.

For the purpose of placing the mica plates seriatim on the strip 3 they are stacked in a magazine 36 comprising a hollow metal shaft in the lower end of which a piston is adapted to reciprocate and to serve as a support for the column of mica plates contained in the magazine. Into the bottom of the magazine there opens a pipe 37 by means of which connection is made to an air-pressure supply. The pressure thus exerted on the underside of the piston is sufficient to support its weight and that of the mica plates and to ensure that the uppermost plate of the stack is in proximity to the upper open end of the magazine 36. If desired, this open end may be provided with a flange or projections directed inwardly in order to prevent the

plates being ejected from the magazine by the air pressure acting on its piston.

For the purpose of transferring the mica plates one by one from the magazine 36 to the operative position of the spray gun 35, the suction picker illustrated more particularly in Figure 6 is employed. This picker comprises a nozzle 38 mounted on an arm 39 attached to a frame 40 which is free to reciprocate in the vertical direction on rods 41, the nozzle 38 being connected by a flexible tube 42 with a suction supply not shown. The rods 41 together with upper and lower members 43 and 44 constitute a framework supported above and below between pivots 45 and adapted to be rocked in the horizontal direction through a right angle. This rocking motion is derived from a cam 46 mounted on the spindle 19 and adapted to act, against the pull of a spring 47, on a cam roller 48 carried by a lever 49 pivoted at 50. Pivoted to the lever 49 is a connecting rod 51 which is also jointed to an arm 52 on the member 44. Thus the nozzle 38 may be brought either into a position immediately above the magazine 36 or above the spray gun 35.

For the purpose of imparting the necessary vertical motions to the frame 40 along the rods 41, there is mounted on the shaft 9 a cam 53 of the shape shown in Figure 6 and adapted to co-operate with a roller 54 carried by a lever 55 pivoted to a fixed member at 56 and having a compression spring 57 acting in opposition to the cam 53. The end of the lever 55 is bifurcated and connected with the frame 40 by trunnions 58. The position of the various elements of the mechanism represented in Figure 6 is that in which the nozzle 38 is in contact with the uppermost mica plate in the magazine 36. On the right-hand lobe of the cam 53 (as viewed in Figure 6) operating on the roller 54, the nozzle 38 is raised and, owing to its suction action, the top mica plate is lifted away from the stack of plates. While the nozzle is in this raised position the cam 46 operates to swing the arm 39 from the position shown in Figure 6, in which the nozzle is above the magazine 36, to the position shown in Figures 1 and 3, in which it is over the aperture in the strip 3 immediately, for the time being, above the spray gun 35. As the right-hand lobe of the cam 53 passes from beneath the roller 54, the frame 40 and with it the arm 39 and nozzle 38 are lowered under the action of the spring 57 until the mica plate carried by the nozzle 38 is in contact with the strip 3.

While the plate is thus held in contact with the strip and over the aperture immediately above the spray gun, it is necessary that the latter shall be actuated in order to perform the silvering operation on the lower surface of the plate. For this purpose, the spray gun 35 is connected with a suitable source of the silvering medium, such as a reservoir, by means of a pipe 59 and also by a pipe 60 with an air-pressure supply 61. This supply is through the medium of a valve 62, Figure 1, 3 and 7, adapted to be opened when a pin 63 extending from it is pressed home. This action is effected by means of a lever 64, pivoted at 65 and adapted to be acted upon by an arm 66 fitted on the shaft 9 and provided with a roller 67 which bears on the lever 64. Thus, once in each revolution of the shaft 9 and at the appropriate moment, the valve 63 is opened and spray is emitted from the gun 35, whereby the lower surface of the mica plate held by the nozzle 38 in contact with the strip

3 is silvered. If desired, the spray gun 35 may be provided with a shield which in normal operation of the apparatus is removed immediately before emission of the silvering medium provided that a mica plate is in position for silvering, such removal not, however, being effected if for any reason a plate is absent. The removing mechanism might, for instance, be actuated by a suction device connected with the tube 42; if then there be no mica plate over the nozzle 38, the suction in this tube is destroyed or sufficiently reduced to ensure that the removal mechanism is not operated and the spray gun 35 remains shielded.

The mica plate having been silvered on its lower surface, it is necessary that it shall remain on the strip 3, and for this purpose the suction supply to the nozzle 38 must be cut off. To this end there is interposed in the tube 42 a valve comprising a cylinder 68 having a plunger 68a actuated, against the tension of a spring 69, by a cam 70 on the shaft 9. This valve is so constructed as to maintain suction over the greater part of each cycle of operations represented by one revolution of the shaft 9, but to open a port 68b in the cylinder 68 to atmosphere so as to break down the suction and produce atmospheric pressure at the nozzle 38 at the moment at which the silvering is completed and the nozzle is about to be raised in order to pick up the plate which has now become uppermost in the stack contained in the magazine 36. For this latter purpose the plunger 68a closes the port 68b to atmosphere, whereby the suction at the nozzle 38 is restored shortly after the latter has been raised from the mica plate deposited on the strip 3 and carried forward thereby. In order to raise the nozzle 38 from the strip 3, the left-hand lobe of the cam 53 (as viewed in Figure 6) comes into operation and maintains the frame 40 and nozzle 38 in the raised position during action of the cam 46, which allows the lever 49 to rock under pull of the spring 47 and turn the arm 39 counterclockwise (as seen in Figure 1) through a right angle, so that the nozzle 38 is once again above the magazine 36. The portion of the cam 53 between the lobes then becomes operative so that the nozzle 38 is lowered into contact with the uppermost mica plate on the stack and the cycle of operations is repeated.

Meanwhile, the strip 3 is moved forward step by step carrying with it the series of mica plates, after each has been silvered on its lower surface. In its travel toward the winding-off roll 8 and immediately after the silvering operation, the strip 3 bearing the mica plates may be passed through, or in proximity to, some heating element whereby preliminary drying of the silvering coating may be effected. Before the strip 3 reaches the winding-off roll 8 it becomes necessary to remove the mica plates therefrom, and for this purpose the suction device illustrated in Figures 2, 4, and 8 is employed.

This mechanism serves to transfer the mica plates one by one from the strip 3 to an endless travelling belt 71 whereby the plates are conveyed through an oven 72 for heat treatment. It comprises a hollow arm 73 having a nozzle 74, this latter being shown in Figures 2 and 4 in the position in which it is about to pick up a mica plate from the strip 3, and in Figure 8 immediately after it has deposited a plate on a platform in readiness for actual transfer to the belt 71. The arm 73 is carried by a hollow spindle 75, mounted so as to be capable of rocking and fitted with a

pinion 76 engaging a segmental rack 77, pivoted at 78. In proximity to this mechanism there is fitted on the shaft 9 a cam 79 which bears on a roller 80 carried by a lever 81 pivoted at 82 and connected with the segmental rack 77 by a link 83, the connection of the latter with the lever 81 being by means of a pivot 84, the location of which in a slot 85 may be varied in order to determine the degree of oscillation of the rack 77 and therefore of the hollow arm 73. The hollow pivot 75 of the arm 73 is connected by a tube 86 to the suction supply so that normally during the back-and-forth stroke of the arm 73 there is suction at the nozzle 74. By this means when, during a halt in the motion of the strip 3, the nozzle 74 is brought down into contact with one of the mica plates and immediately subsequently is raised, the mica plate is carried with it through the travel of the arm amounting to nearly 180°. However, as the arm 73 approaches the end of its backward stroke, the nozzle 74 passes between a pair of parallel plates 87 the distance between which, while being sufficient to allow passage of the nozzle, is such as to retain the mica plate, whereof the edges extend beyond the nozzle. In order to permit this deposit of the mica plate on the platform constituted by the plates 87, it is arranged that a port in the hollow spindle 75, not shown, shall co-operate with a port leading to the atmosphere whereby the suction at the nozzle 74 is relieved. Further, the cam 79 is preferably so shaped that, as the nozzle 74 passes between the plates 87, its rate of motion is reduced so as to avoid any tendency for the mica plate deposited on the plates 87 to rebound. It will be observed that the silvered surface of each mica plate is now uppermost.

Mechanism for transferring the mica plates on to the endless belt 71 then comes into operation, this mechanism comprising a bar 88 whereof the end is fashioned as a claw 89, adapted, when the bar 88 is reciprocated, to bear on the rear end of the mica plate resting on the plates 87 and, on return movement of the bar, to slide the mica plate along the plates 87 and finally to transfer it to the endless belt 71. Reciprocatory movement of the bar 88 is effected by a cam 90 fitted on a spindle 91 driven from the shaft 9 by bevel gearing 92, this cam acting, against a tension spring 93, on a roller 94 mounted on a lever 95 pivoted at 96 and slotted at its upper end to engage a pin 97. This pin is attached to a carriage 98 adapted to reciprocate along slide bars 99, the pin 97 extending through the carriage and serving as a pivot for the bar 88. In order that the claw 89 on the bar 88 shall not come into contact with the mica plate resting on the plates 87 during travel of the plate 88 from right to left as seen in Figures 2, 4 and 8, there is provided a ramp consisting of a short length of spring steel 100 whereof the left-hand end is raised, being attached to a block 101, while the right-hand end is sufficiently depressed to ensure that a pin 102 projecting from the bar 88 shall ride over the ramp. As, however, the bar 88 moves from right to left, after the pin 102 has travelled the length of the ramp 100, it drops over the raised end thereof, so that the claw 89 rests on the plates 87 and, on the return movement of the bar, serves to drag the mica plate along the plates 87 and transfer it on to the endless belt 71, which is in continual movement toward the oven 72 and whereof the terminal roller 103 is conveniently located in proximity to the bars 87. The mica plate having been removed from these bars, the

way is open for return motion of the nozzle 14 in order to pick up the succeeding mica plate from the strip 3, the cam 19 being appropriately shaped in order to effect this return at the required moment and the suction at the nozzle being restored.

What we claim and desire to secure by Letters Patent of the United States is:

1. Apparatus for depositing films of metal on a series of plates, comprising in combination a magazine wherein said plates are stacked, means for feeding a continuous strip of paper past and in close proximity to the magazine in the direction of the length of the paper in a step by step manner, a single, continuously operating drive unit of substantial length extending lengthwise of the paper strip, and mechanism coupled with and operated by said unit at each halt of said strip, including a punching tool for cutting an aperture in said strip, a pivoted arm, means for oscillating said arm between said magazine and a position on said strip over one of said apertures cut during a previous halt of said strip, means for effecting the picking up of a plate by the arm from the magazine and the depositing of the plate on the strip, a spray gun operatively located to spray paint through said aperture onto a plate transferred by said arm on said magazine to said strip, and means for removing from said strip one of said plates painted during a halt of said strip.

2. Apparatus as in claim 1, wherein the said means for picking up and depositing the plate comprises a suction nozzle carried by the arm adapted to effect the transfer of the plates one by one to positions on said paper strip over said apertures.

3. Apparatus as in claim 1, wherein the said means for picking up and depositing the plates comprises a suction nozzle carried by the arm and connected to a source of suction, and said means for oscillating said arm comprising a coupling between the arm and said drive unit including a cam, a cam actuated lever and a connecting rod between the lever and the arm, for automatically bringing said nozzle at each halt of said strip into contact with the uppermost plate of a stack within said magazine, raising the nozzle from the magazine together with the uppermost plate held in contact with the nozzle by suction, transferring the nozzle to a location in line with one of the apertures in said paper strip and lowering the nozzle over said aperture.

4. Apparatus as in claim 1, wherein the said means for picking up and depositing the plates comprises a suction nozzle carried by the arm, means forming a coupling between the arm and the drive unit operating at each halt of said strip for maintaining said nozzle during each transfer operation for an interval of time in proximity to said paper strip, said spray gun being located on the side of said strip opposite to said nozzle, and means to operate said spray gun during said interval to silver the surface of one of said plates held for the time being by said nozzle.

5. Apparatus as in claim 1, wherein the said means for picking up and depositing the plates comprises a suction nozzle carried by the arm and connected to a source of suction, said means for oscillating the arm comprising a coupling between the arm and the unit operating at each halt of said strip for causing said nozzle to transfer a plate from said magazine to said paper strip, said spray gun being designed to function during

proximity of said nozzle to said paper strip, means for relieving suction pressure at said nozzle upon completion of operation of the gun, and means for restoring said nozzle to operative position relative to said magazine for taking up another plate.

6. Apparatus as in claim 1, wherein the mechanism for removing the plates from the paper strip comprises a pivotally mounted suction nozzle and means for intermittently swinging the nozzle to a position to pick up a plate from the strip.

7. Apparatus as in claim 1, wherein the mechanism for removing the plates from the paper strip is constituted by a hollow arm connected to a source of suction, a suction nozzle on said arm, a platform, and means forming a coupling between the nozzle and the drive unit operating automatically at each halt of said strip for rocking said arm whereby said plates are transferred one by one from said paper strip to said platform.

8. Apparatus as in claim 1, wherein the mechanism for removing the plates from the paper strip is constituted by a hollow arm connected to a source of suction, a suction nozzle on said arm, a platform constituted by a pair of plates, and means forming a coupling between the nozzle and said drive unit operating automatically at each halt of said strip for rocking said arm whereby said plates on said strip are transferred one by one from said paper strip to said platform, said pair of platform plates being so located that such nozzle, in its transferring movement, passes between them.

9. Apparatus as in claim 1, including a platform, the said means for moving the plates from the strip comprising a movable suction nozzle, means for moving the suction nozzle in a prescribed path to transfer said plates one by one from said paper strip to said platform, a roller, means for rotating said roller, an endless belt around said roller, and means for transferring each of said plates from said platform to said belt.

10. Apparatus as in claim 1, including a platform, the said means for moving the plates from the strip comprising a movable suction nozzle, means for moving the suction nozzle in a pre-described path to transfer said plates one by one from said paper strip to said platform, a roller, means for rotating said roller, an endless belt around said roller, a claw, means for oscillating said claw between said platform and said belt, and means for holding said claw out of contact with said platform during oscillation in one direction, but allowing it to make contact with said platform during oscillation in the reverse direction and thereby to bear on the end of one of said plates resting on said platform whereby said plate is transferred to said endless belt.

11. In apparatus for depositing films of metal upon plates including an apertured masking strip moved intermittently in the direction of its length and spraying means located beneath the strip for discharge against the underside thereof; means for supporting a stack of plates adjacent to the strip, a plate transfer mechanism adjacent to the plate stack supporting means and functioning automatically to transfer a plate from the stack into position over an opening on the strip between the periods of movement of the strip, heat treating means for the sprayed plates comprising a carrier belt disposed in spaced parallel relation with said strip, and means for transferring a plate from the apertured strip to said belt comprising a suction nozzle, supporting means for

said suction nozzle for swinging the nozzle on an axis between and paralleling the strip and belt, said nozzle when in one position being in contact with the top of a plate on the apertured strip and when in another position being adjacent to said belt, means for swinging said nozzle from one position to the other, and means for effecting the removal of the plate from the nozzle and onto the belt when the nozzle is in the said other position.

12. In apparatus of the character stated in claim 11, the said last named means comprising a pair of spaced plates between which the nozzle passes for the removal of the nozzle carried plate, and reciprocating means overlying the said pair of plates for shifting the nozzle transferred plate onto said belt.

13. In apparatus of the character stated in claim 11, the said means for transferring the sprayed plate from the nozzle to the belt, comprising a pair of relatively long platform plates disposed in spaced parallel relation over and extending lengthwise of the belt at one end thereof, said nozzle being adapted to pass between the platform plates to leave the sprayed plate thereon, a claw member supported for movement longi-

tudinally of and over the platform plates, means for reciprocating said claw member, and means for moving the claw member over the top of the sprayed plate when the claw member moves in one direction and for lowering the claw member to engage the sprayed plate when the claw member moves in the opposite direction to effect the shifting of the sprayed plate from the platform plates onto the belt.
